DESIGN FOR A CATCH HANDLE

Earl M. Borchers, Rockford, Ill., assignor to
American Cabinet Hardware Corporation,
Rockford, Illinois, Rockford, Ill., a corporation
of Illinois

Application August 8, 1945, Serial No. 121,315

Term of patent 7 years

(Cl. D10—8)

To all whom it may concern:

Be it known that I, Earl M. Borchers, a citizen of the United States, residing at Rockford, in the county of Winnebago and State of Illinois, have invented a new, original, and ornamental Design for a Catch Handle, of which the following is a specification, reference being had to the accompanying drawing, forming a part thereof.

Figure 1 is a side elevational view of a catch handle embodying my new design.

Fig. 2 is a front elevational view of the same.

Fig. 3 is an elevational view of the upper end of the catch handle.

The dominant features of the design reside in the portion shown in full lines in the drawing.

I claim:

The ornamental design for a catch handle, substantially as shown and described.

EARL M. BORCHERS.
